UNITED STATES PATENT OFFICE.

JEROME I. WOOD, OF PHILADELPHIA, PENNSYLVANIA.

PROPELLER.

SPECIFICATION forming part of Letters Patent No. 755,426, dated March 22, 1904.

Application filed June 26, 1902. Renewed August 18, 1903. Serial No. 169,943. (No model.)

To all whom it may concern:

Be it known that I, JEROME I. WOOD, a citizen of the United States, residing in the city and county of Philadelphia, in the State of Pennsylvania, have invented certain new and useful Improvements in Propellers, of which the following is a full, clear, and exact description, reference being had to the accompanying drawings, of which—

- 10 Figure 1 is an elevation of my improved propeller looking in a direction as from the bow toward the stern of a boat when the propeller is applied thereto. Fig. 2 is a similar view looking in the opposite direction. Fig. 3 is a 15 view looking upwardly at Fig. 1. Fig. 4 is a side elevation of Fig. 3 looking in the direction of the arrow. Fig. 5 shows section taken, respectively, on planes $x y z$ through a blade, Fig. 3.
- 20 The object of this invention is to provide an improved propeller for boats which shall be of simple construction, efficient, and possess certain marked advantages hereinafter mentioned.
- 25 Referring to the accompanying drawings, 1 denotes the blades—three in the present instance—2 the hub, and 3 the usual opening therethrough for the driving-shaft, to which the propeller is to be secured. Each of the 30 blades is curvilinear in the direction of its length and straight transversely—that is to say, any and all lines drawn upon the inner and outer surfaces of a blade in planes at right angles to the length or chord of the curve of the blade will be straight lines. The two edges 35 1^a and 1^b of the blade are each substantially the arc of a circle; but neither edge can advantageously exceed a semicircle. The edges converge and meet at the outer free end of 40 the blade and also substantially at their inner ends, being there, however, necessarily sufficiently widened, as shown, so as to afford a suitably strong connection with the hub 2. The blade is joined to the hub in such position, 45 as also shown in the drawings, that the edge 1^a , being the inner edge or that toward the bow of the boat, is substantially in a plane passing longitudinally through the major axis of the hub, and the plane of the outer edge is 50 substantially at right angles to the plane of the edge 1^a . Sections of the blade in planes at right angles to both of said planes will be oblique thereto—for example, sections $x y z$, Fig. 5, made, respectively, in planes $x y z$, Fig. 4, are oblique to the plane c , Fig. 5, this being the plane of the edge 1^a . These sections are also oblique to the plane d at right angles to plane c , plane d being that of the edge 1^b and passing through the major axis of the hub. In the particular blades shown the angle e , Fig. 5, formed by the plane c and the side of the blade adjacent to the edge 1^a is forty-five degrees, as is also the angle f , formed by the plane d and the side of the blade adjacent to the edge 1^b . To lessen the pitch of the blade, (without 65 changing the length thereof,) the angle f would be diminished and the angle e correspondingly increased, and to increase the pitch the angle f would be increased and the angle e correspondingly diminished, as indicated, respectively, by the lines g and h in the blade-section y , Fig. 5; but the pitch of the blade of the relative dimensions of those shown in the drawings cannot be diminished by making the obliquity of the blade such as would carry the 70 edge 1^b beyond its present position—that is, for example, as if the side of the blade-section be made to correspond with the line i , Fig. 5—for in such case the said edge would be an arc greater than a semicircle, which would be 75 of no advantage, but the contrary. If the angle f be diminished and angle e increased, as mentioned, the edge 1^b will remain semicircular; but the edge 1^a will be an arc less than a semicircle which will touch the ends of the 80 blade and the point k , Fig. 5—that is, the highest point of the arc or edge 1^a . If the angle f be increased and the angle e diminished, the edge 1^a will remain semicircular and the edge 1^b will be an arc less than a semicircle which will touch the ends of the blade and the point l —that is, the highest point of the arc or edge 1^b . It may also be stated 85 generally that the extent and radius of the arcs of the respective edges of a blade will depend upon the relative length and pitch of the blade; but, as before stated, neither arc should exceed a semicircle.
- 90 Having described my invention, I shall briefly describe its mode of operation. When 95
- 100

the propeller is driven to propel the boat forward—that is, in the direction of the arrow in Figs. 1 and 2—the blades throw the water directly aft in substantially straight lines, the 5 water with which the face of the blade contacts leaving the same as, so to say, a “colum-
nar” body whose width is indicated by the lines *m n*, Fig. 5, and when the propeller is re-
versed to drive the boat backwardly the water
10 will likewise be thrown directly forward, leav-
ing the inner face of the blade as a column
whose width is indicated by the lines *o p* in said
figure.

Having thus described my invention, I claim
15 as new and desire to secure by Letters Patent—
A propeller whose blades are curvilinear in

the direction of their length, the sides of the
blades being straight transversely, and their
edges convergent arcs in planes at right angles
to each other, the inner or leading one of said
edges being substantially in a plane passing
20 longitudinally through the major axis of the
hub, and the outer one of said edges in a plane
at right angles to said axis, substantially as set
forth.

In testimony whereof I have hereunto
affixed my signature this 16th day of June,
A. D. 1902.

JEROME I. WOOD.
